UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

STEM-WINDING AND STEM-SETTING WATCH.

1,361,613.

Specification of Letters Patent.

Patented Dec. 7, 1920.

Application filed September 6, 1919. Serial No. 322,020.

To all whom it may concern:

Be it known that I, WILSON E. PORTER, a citizen of the United States, residing at New Haven, in the county of New Haven 5 and State of Connecticut, have invented a new and useful Improvement in Stem-Winding and Stem-Setting Watches; and I do hereby declare the following, when taken in connection with the accompanying drawings and the characters of reference marked thereon, to be a full, clear, and exact description of the same, and which said drawings constitute part of this application, and represent, in—

Fig. 1 a view in elevation of the inner face of the front movement-plate of a stem-winding and a stem-setting watch embodying my invention, the rear movement-plate and the watch trains being removed and my improved mechanism being shown in its winding adjustment.

Fig. 2 a view, showing the front face of the front movement-plate with my improved mechanism as adjusted for setting.

Fig. 3 an enlarged broken view partly in elevation and partly in vertical central section, showing the winding-and-setting stem coupled with the shifting-lever which is at this time in its forward or operating position.

Fig. 4 a corresponding view showing the shifting-lever as moved from front to rear and so disengaged from the coupling-terminal of the winding-and-setting stem, 35 which may now be removed or if removed, inserted.

Fig. 5 a detached view in front elevation of the shifting lever.

Fig. 6 a plan view thereof.

Fig. 7 an edge view thereof.

Fig. 8 a detached view in elevation of the winding-and-setting stem and its crown.

Fig. 9 a broken view in front elevation of the front movement-plate, showing the laterally movable pivot by which the secondary winding-and-setting wheel is carried.

Fig. 10 a detached view in side elevation of the same pivot, together with its spacing-collar and the secondary winding-and-setting wheel.

Fig. 11 a broken view in rear elevation of the upper portion of the rear movement-plate, showing the locking-screw mounted therein for normally holding the shifting-

lever in its forward or operating position,

the arbor being shown as turned preparatory to sliding the lever from front to rear.

My invention relates to an improvement in that class of stem-winding and stem-setting watches in which the stem is pulled 60 out for setting, the object being to provide a simple, compact, convenient and reliable winding and setting mechanism particularly designed to reduce the number of parts employed to the minimum, whereby cheapness 65 of construction is secured and liability to derangement avoided. In another view of my invention, it is designed to dispense with the use of the wheel-carrying yokes heretofore employed in kindred watch structures. 70

With these ends in view, my invention consists in a pivotal shifting-lever adapted to be coupled with the winding-and-setting stem and to shift a winding-and-setting 75 wheel from the winding train to the setting train and vice versa and laterally movable for disengagement from and reengagement with the stem. My invention further consists in further details of construction as will hereinafter be described and pointed 80 out in the claims.

In carrying out my invention as herein shown, I employ a depending shifting-lever 2, mounted at its upper end upon a shoulder 3 at the outer end of a spacing-hub 4 on an 85 arbor 5, the rear end of which has rocking and sliding movement in the rear movement-plate 6, and the forward end of which has rocking and sliding movement in a spacing-bushing 7 mounted in the front movement-plate 8 and extending rearward therefrom between the two movement-plates.

The said shifting-lever 2 is formed with an upwardly extending coupling-arm 9 bent to form a three sided clearance space 10, 95 and having its forwardly bent upper end formed with an open slot 11 for the reception of a coupling-terminal 12 at the lower end of the removable winding-and-setting stem 13, which is furnished with the usual 100 crown 14, the said stem having a squared portion 15 located adjacent to its coupling-terminal 12 and passing through a squared opening formed in a primary stem-winding and stem-setting wheel 16, arranged at a 105 right angle to the stem and mounted upon a horizontal bridge 17 located between the upper edges of the plates 6 and 8 at the bottom of notches 18 therein.

The lower end of the shifting-lever 2 is 110

formed with an angular shifting-slot 19, having an upper arm 20 and a lower arm 21, the upper arm having an inclined operating-face 22, and the lower arm having a locking-undercut 23. The said slot receives the rearwardly projecting end of the laterally movable pivot 24 of the secondary winding-and-setting wheel 25, which constantly intermeshes with an intermediate winding-and-setting wheel 26, mounted upon the outer face of the front movement plate 8 and in turn constantly intermeshing with the primary stem-winding and stem-setting wheel 16.

15 The pivot 24 has lateral movement in a slot 27 formed in the front movement-plate 8, its forward end projecting through the said slot and carrying the wheel 25 aforesaid. A collar 28 integral with the pivot 24 bears upon the inner face of the front movement-plate, and coacts with the wheel 25 in preventing the longitudinal movement of the pivot, while not interfering with the lateral movement of the pivot in the slot 27, 25 which is made sufficiently long to provide for the lateral shifting of the wheel 25 so as to intermesh it with the main winding—or plate wheel 29 or the plate setting-wheel 30. The periphery of the collar 28 is engaged by 30 a spring 31 applied to the inner face of the front movement-plate and exerting a constant effort to maintain the pivot 24 in the left-hand end of the slot 27 (Fig. 1), and hence the wheel 25 normally in mesh with 35 the main winding- or plate wheel 29.

Normally, the shifting-lever 2 is maintained in its forward or operating position in which it is coupled with the coupling-terminal 12 of the stem 13, by means of a 40 shoulder stud 32 (Fig. 11), mounted in the upper edge of the rear movement-plate 6 and having a portion of its head cut away to clear the arbor 5 when it is desired to shift the lever 2 from front to rear, that is, 45 from the position in which it is shown in Fig. 3, to the position in which it is shown in Fig. 4, whereby the slotted coupling-arm 9 of the lever is cleared from the coupling-terminal 12 of the stem 13 to permit the same 50 to be removed or replaced. When the lever 2 is moved from front to rear as described, the rear face of the spacing-hub 4 engages with the inner face of the rear movement-plate and so limits the rearward movement 55 of the arbor 5; on the other hand, the movement of the arbor 5 from rear to front is limited by the engagement of the shoulder 3 of the hub 4 with the spacing-bushing 7 in the front movement-plate.

60 Normally, the watch is set for winding, at which time the spring 31 engaging with the collar 28, holds the laterally movable pivot 24 in the left-hand end of the slot 27, whereby the wheel 25 is maintained in mesh 65 with the main winding- or plate wheel 29.

At this time, the rear end of the pivot 24 will be located in the upper arm 20 of the angular shifting-slot 19, as shown in Fig. 1. Now if the stem 13 is pulled outwardly by its crown 14, the inclined operating-face 22 70 of the arm 20 of the slot 19 will act upon the lower face of the pivot 24 and cause the same to be shifted to the right-hand end of the slot 27 against the tension of the spring 31, whereby the secondary winding-and-setting wheel 25 will be demeshed from the main winding-wheel 29 and intermeshed with the plate setting-wheel 30, as shown in Fig. 2. The lifting of the lever 2, as described, causes the pivot 24 to enter the 80 lower arm 21 of the shifting slot 19 and ride into the locking-undercut 23 thereof, whereby the lever 2 is locked in its lifted or setting position, in which it will be retained by the said undercut 23 during setting. 85 When the watch has been set, the stem 13 is pushed inwardly with the effect of swinging the lever 2 from right to left, causing the pivot 24 to ride out of the undercut 23 and out of the arm 21 of the shifting-slot 19 90 and resume its normal position in the upper arm 20 of the said slot, in which it will be retained by the spring 31 until the stem is again pulled out for setting the watch. By my improvement I omit the use of a pivotal 95 yoke or lever carrying one or more wheels of the winding and setting mechanism and reduce the number of parts as well as liability to derangement. In my improved mechanism, the secondary winding-and-setting 100 wheel 25 is mounted independently of the part—the lever 2—by which it is shifted for changing from winding to setting and vice-versa.

I claim:—

1. A stem-winding and stem-setting watch, pulling out to set, having a winding-and-setting stem, a shifting-lever adapted to be connected therewith, and a winding-and-setting wheel mounted independently of the said lever in one of the movement-plates of the watch for lateral movement therein and adapted to be shifted directly by the said lever into engagement with members of the winding and setting trains of the watch. 110

2. A stem-winding and stem-setting watch, having a winding-and-setting stem, a shifting-lever pivotally mounted between the movement plates of the watch, and adapted to be swung by the said stem, and a winding-and-setting wheel mounted independently of the said lever in one of the movement-plates of the watch for lateral movement therein and adapted to be shifted directly by the said lever into position for engagement with members of the winding and setting trains of the watch. 120

3. A stem-winding and stem-setting watch having a winding-and-setting stem, a shifting lever adapted to be coupled with

105

115

120

125

130

- the said stem for operation thereby and to be uncoupled therefrom to permit the removal and replacement thereof, and a winding-and-setting wheel mounted in one of the movement-plates of the watch for lateral movement therein and positioned for direct engagement with the said lever by which it is controlled in being shifted into its winding and setting positions.
4. A stem-winding and stem-setting watch having a winding-and-setting stem, a shifting lever located between the movement-plates of the watch and adapted to be coupled with and uncoupled from the said stem, a rocking and longitudinally sliding arbor carrying the said lever, and a winding-and-setting wheel mounted in one of the movement-plates of the watch for lateral movement therein and positioned for direct engagement with the said lever by which it is controlled in being shifted into its winding and setting positions.
5. A stem-winding and stem-setting watch, having a winding-and-setting stem, a shifting-lever adapted to be coupled with and uncoupled from the said stem by which it is operated, an arbor carrying the said lever and having rocking and longitudinal sliding movement in the movement plates of the watch, a winding-and-setting wheel mounted independently of the said lever, in one of the movement-plates of the watch for lateral movement therein and adapted to be shifted by the said lever for being engaged with members of the winding and setting trains, and means for normally holding the said arbor in position for maintaining the stem and lever in coupled engagement, the said means being located upon the outer face of one of the movement-plates of the watch in position to be moved into and out of engagement with one end of the said rocking and sliding arbor.
6. A stem-winding and stem-setting watch, having a winding-and-setting stem, a shifting-lever adapted to be coupled with and uncoupled from the said stem, an arbor carrying the said lever and journaled in the movement plates of the watch for rocking and sliding movement therein, a spacing-hub upon the said arbor for limiting the sliding movement in the direction of the coupling thereof, and a winding-and-setting wheel mounted independently of the said lever in one of the movement-plates of the watch for lateral movement therein and adapted to be shifted by the said lever for engagement with members of the winding and setting trains of the watch.
7. A stem-winding and stem-setting watch, having a winding-and-setting stem, a shifting-lever located between the movement plates of the watch and adapted to be coupled with and uncoupled from the said stem, an arbor mounting the said lever and journaled in the said plates for rocking and sliding movement therein, a winding-and-setting wheel mounted independently of the said lever in one of the movement-plates of the watch for lateral movement therein and adapted to be shifted by the said lever for engagement with members of the winding and setting trains of the watch, and means bearing upon the outer face of the rear movement-plate of the watch for engaging with the rear end of said arbor for holding the same at the limit of its forward sliding movement in which the said lever is coupled with the said stem.
8. A stem-winding and stem-setting watch, having a winding-and-setting stem, a shifting-lever adapted to be coupled with the said stem and formed with an angular shifting slot, and a winding-and-setting wheel mounted independently of the said lever upon a pivot laterally movable in one of the movement plates of the watch entering the said slot by which, when the lever is shifted, the said wheel is shifted for engagement with members of the winding and setting trains of the watch.
9. A stem-winding and stem-setting watch, having a winding-and-setting stem, a shifting-lever operated thereby and formed with an angular slot having an inclined operating-face and a locking-undercut, a winding-and-setting wheel for engagement with members of the winding and setting trains of the watch, and a laterally movable pivot mounted directly in one of the movement-plates of the watch, carrying the said wheel and entering the said slot for co-action with the operating-face and locking-undercut thereof.
10. A stem-winding and stem-setting watch, having a winding-and-setting stem, a shifting-lever operated by the said stem, a winding-and-setting wheel, a pivot mounting the said wheel, passing through a slot in one of the movement-plates of the watch, provided with a spacing collar and co-acting directly with the said lever by which it is laterally moved in the said slot for shifting the said wheel into engagement with members of the winding and setting trains, and a spring engaging with the said spacing-collar and normally maintaining the watch adjusted for setting.
11. A stem-winding and stem-setting watch, having a winding-and-setting stem, a shifting-lever provided with a coupling-arm receiving the said stem and with an angular shifting-slot, a rocking and longitudinally sliding arbor carrying the said lever, and a winding-and-setting wheel mounted upon a laterally movable pivot entering the said slot in the lever for operation thereby to shift the said wheel into engagement with members of the winding and setting trains of the watch, the said pivot being mounted

for lateral movement directly in one of the movement-plates of the watch.

12. A stem-winding and stem-setting watch, having a winding-and-setting stem, a shifting-lever having an upwardly extending slotted coupling-arm and an angular shifting-slot comprising upper and lower arms, a rocking and longitudinally sliding arbor journaled in the said plates and carrying the said lever, means for limiting the longitudinal movement of the said arbor and holding it in the position in which its coupling-arm is coupled with the said stem, and a winding-and-setting wheel adapted to

co-act with members of the winding and setting trains, and carried by a laterally movable pivot extended into the said angular shifting-slot of the shifting-lever for operation thereby, the said pivot being mounted for lateral movement in one of the movement-plates of the watch. 15 20

In testimony whereof I have signed this specification in the presence of two subscribing witnesses.
